OF CLINTON, IOWA

IRONING-BOARD STRUCTURE

Application filed December 31, 1928. Serial No. 329,609.

My present invention relates to an ironing board structure.

The object of my invention is to provide an ironing board structure including a board of 5 the type that is designed to fold up into a wall case when not in use.

More particularly, it is my purpose to provide a combination structure in which an ironing board may be folded into a case, 10 which is close to the floor, so as to permit the board to be installed where head room is limited.

Another purpose of my invention is to provide such a structure which can be installed 15 in a wall between studding of standard spacing.

A further object is to provide a structure including a case member which may be hung 20 as a door of a closet or cabinet and may also serve as an adjustable support for the ironing board.

Still another object is to provide in such 25 a structure an ironing board readily and quickly adjustable to proper height by the same manipulation which sets the ironing board in position for use.

An additional purpose is to provide suitable means for locking the board in ironing 30 position, so that it can not accidentally fall down.

Still another purpose is to provide such 35 a structure that the ironing board support also serves as a door and thus eliminates the necessity for other hinged doors, which might otherwise take up wall space or interfere with the use of the board.

Another purpose is to provide in the combination an adjustable sleeve board which is 40 readily demountable.

Finally, it is my purpose to provide such a 45 structure having parts so constructed and arranged as to afford a rigid support for the ironing board when in use, and which is yet easily and conveniently handled and adjusted.

With these and other objects in view, my 50 invention consists in the construction, combination and arrangement of my ironing board structure, whereby the objects contemplated are attained, as hereinafter more fully

set forth, pointed out in my claims, and illustrated in the accompanying drawings, in which:

Figure 1 is a perspective view of an ironing board structure embodying my invention. 55

Figure 2 is a vertical, sectional view through the upper portion of the same and through part of the ironing board when the latter is lowered to working position.

Figure 3 is a perspective view of the structure installed in a wall. 60

Figures 4, 5 and 6 are side elevations illustrating the ironing board structure in different positions of the movable parts thereof, during the adjustment of such parts from 65 folded up to working position.

Figure 7 is a front elevation of the structure with the ironing board in working position.

Figure 8 is a vertical, sectional view 70 through the casing illustrating the manner of securing the lower part of the ironing board support in position for holding the ironing board for work.

Figure 9 is a top view of the inner end of 75 the ironing board when in position for work, parts being broken away and parts being shown in section to illustrate the locking device; and

Figure 10 is a detail, longitudinal sectional view through the inner part of the ironing board illustrating the locking device. 80

It may be mentioned that my improved structure may be built as a unit in the factory so that it can be shipped and installed 85 as a unit.

In the drawings herewith, I have shown a case, which has the panel 10 forming a back member, the forwardly extending shallow 90 side jambs or walls 11, the head jamb or wall 12 and the bottom jamb or wall 13.

The face of the case is trimmed with casing 14.

The inner faces of the side jambs 11 in 95 the lower parts thereof are provided with grooves 16 in which are inset metal channels 18. Near the upper portion of each channel 18, the bottom of that channel and the jamb beyond it are provided with a series of verti- 100

cally spaced holes 20 to receive the locking bolts hereinafter referred to.

Secured to the inner faces of the side jambs 11 at the tops thereof near their front edges are wear plates 22 shown in Figure 2. Holes 24 extend through the wear plates 22 and into the jambs 11.

In the inner faces of the jambs 11 spaced rearwardly from the holes 24 are holes 26 (see Figure 1) to receive the locking bolts of the sleeve board hereinafter referred to.

In the inner faces of the jambs 11 above and rearwardly from the grooves 16 are vertically spaced holes 28. (See Figure 2.)

For closing the case, I provide a two-part door comprising the upper and lower halves 30 and 32 hinged together as at 34.

There is provided an ironing board 36, one-half of which is secured to the inner face of the door section 32. The ironing board is provided at what is its lower end when the parts are folded up into the case with a locking device and the door member 30 is provided with a locking device, which is similar, except for the springs to be hereafter mentioned.

I shall now describe this locking device. For convenience, it may be said that in referring to the upper and lower parts of the various elements, I am referring to them when in their closed position as shown in Figure 3.

In the lower end of the ironing board 36, there is cut clear across the board a groove 40, which is partially filled by a spline 42 glued into the groove, so as to leave a transverse opening 44 across the board. (See Figures 2, 9 and 10.)

A hole is cut through the board as at 46 to bisect the passage 44. The ends of the hole 46 are closed by discs A and B which rotate freely in the holes.

The disc B comprises a disc-like sheet of metal 48 rigidly secured to a second disc-shaped piece of metal 50 having the annular in-turned flange 52 received in the hole 46.

The disc A consists of a disc-like sheet of metal 54 having an out-turned annular flange 56 received in the hole 46 and a disc member 58 of greater diameter, having a central cupped portion 58^a secured to the portion 54.

A key 60 has two legs 62 extending through the discs A and B and receiving the lock nuts 64. The legs 62 extend respectively through the offset ends 66 and 68 of locking bolts or rods 70 and 72 slidably received in the passage 44 and projecting through plates 74 and 76 secured to the side edges of the ironing board 36.

Thus it will be seen that by rotating the key 60, the locking bolts 70 and 72 may be simultaneously projected or withdrawn.

For normally yieldingly holding the parts in their position with the locking bolts pro-

jecting, I provide a spring 78, such as that shown for instance in Figure 9.

When the ironing board is in its folded up position, the outer ends of the bolts 70 and 72 project into the channels 18, in which these bolts may slide up and down.

In the upper end of the door member 30 is mounted a locking device, which is similar, except that in some instances, the spring 78 is omitted. The locking bolts of this latter locking device coact with the holes 24 (Figure 2) for locking the doors in their case closing position.

Secured to the side jambs 11 rearwardly from the channels 18 are upright members 80, each having a series of notches 82. When it is desired to move the parts from their positions shown in Figure 3 to position where the ironing board is ready for use as shown in Figure 1, the operator manipulates the locking device at the upper end of the door member 30, which for convenience of reference is indicated by the reference numeral C for withdrawing the bolts of such locking device from the holes 24.

The two door members and the ironing board are then swung on the lower locking bolts 70 and 72 as pivots downwardly and outwardly to the position shown in Figure 4.

The door member 30 is then swung downwardly away from the ironing board to the position shown for instance in Figure 5 until it rests on the floor. Then the lower end of the ironing board is slid upwardly from its position shown in Figure 5 to its position shown in Figure 6. During such sliding movement, the lower locking bolts 70 and 72 slide in the channels 18.

The spring 78 tends to yieldingly force the bolts outwardly to thus keep them projected into the channels 18 and to cause them to enter the lower holes 20. It will be, understood, of course, that the key 60 may be manipulated for controlling the bolts for causing them to enter the holes 20 at any desired height. After the bolts have been projected into the holes 20, the spring 78 prevents any accidental removal of the bolts from the holes.

It will be noted that the spline 42 is cut away for a portion of its length adjacent to the passage 44 as at 42^a on one side of the hole 46, whereas the material of the board itself is cut away along the passage 44 on the other side of the hole 46 as indicated at 36^a.

It will then be noted that the spring 78 is of peculiar construction, comprising a resilient member extending across between the legs 62 of the key 60 and thence bent around them to form similar spirals, terminating on opposite sides of the hole 46 where the ends of the spring member are secured to the material of the ironing board as indicated for instance at 78^a and 78^b in Figure 9.

The parts are so arranged that when the

key 60 is rotated to one limit of its movement for withdrawing the bolts 70 and 72 the offset ends 66 and 68 engage and limit such rotary movement. Rotary movement in the other direction is limited by engagement of the bolts 70 and 72 with the walls of the passage 44. When the bolts are thus extended and are received in the proper holes 20 the door member 32 is then swung toward the case and its lower edge is inserted into an opposite pair of notches 82 (see Figures 1 and 8).

It will be seen that this operation requires that the locking bolts in the door member 30 be withdrawn while the door member 30 is being adjusted to the proper notches 82. The locking bolts are then projected into the channel 18. When this is done, the door member 30 will be rigidly locked in its position shown in Figures 1 and 8, and the ironing board will be rigidly held for use.

The operations necessary for returning the ironing board and the door members to the position shown in Figure 3 will be obvious.

I preferably provide a detachable or demountable sleeve board for use with my ironing board construction. This consists of a sleeve board proper 84. One end of this sleeve board has a frame consisting of a transverse member 86 extending across the end of the board to the opposite side jambs 11, and is provided with the portions 88 extending at right angles to it, as shown in Figure 1. From the portions 88, frame members or portions 90 are inclined to the side edges of the board 84 and secured thereto as at 92.

The sleeve board 84 has a locking device D similar to the first locking device hereinbefore described.

The locking bolts 70 and 72 of the locking device D project away from the board 84 and through the frame portions 88 as shown in Figure 1.

By letting these last-named locking bolts 70 and 72 project into the holes 26 (Figure 1), the sleeve board may be hung as shown in Figure 2.

Secured to the sleeve board 84 spaced from the ends thereof by pivotal connections are the arms 94 of a supporting bail 96.

When it is desired to use the sleeve board with the ironing board, the locking device D is manipulated to withdraw its locking bolts from the holes 26, and these locking bolts are then selectively inserted into the desired holes 28 (Figure 2). The bail 96 is dropped to rest on the ironing board 36 as shown in Figure 1, and the sleeve board is ready for use.

An ironing board structure of the kind referred to herein has a large number of advantages, some of which will be readily inferred from the statement of the objects and the description of the device.

It will be seen that an ironing board struc-

ture of this kind can be manufactured and then shipped and installed as a unit between studding in a wall, and will have the appearance of a closet or cabinet. There are no parts which project into the room when the ironing board is folded up.

The door members which serve to close the case when the device is folded up serve to strengthen and support the ironing board when it is in position for use. They eliminate the necessity for having hinged doors on the case, which might be in the way for ironing operations or interfere with the use of the room when the ironing board is up.

An ironing board of satisfactory length can be employed because the case stands close to the floor, and can be put in any room of ordinary height. The ironing board is quickly and easily adjusted to any of its various positions and is rigidly supported in its position for use.

In making such adjustment, there is a considerable advantage in having the lower end of the ironing board trunnioned in such manner that it travels freely in the grooves in the jambs and in providing trunnioning means, which will serve as locking means for holding this lower end of the board in its raised position. The board might be held and supported in the position shown in Figure 6, if it were desired for any reason to leave it so. It is preferable, however, to arrange the member 32 as shown in Figure 1, thus leaving the space under the board as nearly free as possible and locking the member 32 against accidental displacement. The whole casing and ironing board structure herein shown may be arranged to serve as a broom case, if that is desired.

It will be of course understood that some changes may be made in the details of the construction and arrangement of the parts of my improved ironing board structure without departing from the spirit and purpose of my invention, and it is my intention to cover by my claims, any modified forms of structure or use of mechanical equivalents which may be reasonably included within the spirit of my invention and the scope of my claims.

I claim as my invention:

1. In a structure of the class described, an ironing board, a locking device therefor comprising opposite bolts slidably supported at their outer ends only in the ironing board, a key for sliding said bolts simultaneously endwise said key being rotatably supported on said board and including a pair of legs off center of the key, said legs being pivoted to the inner end of said bolts.

2. A retractile bolt construction comprising, rotatable discs mounted in the ends of an opening through a board and on opposite sides of the board, a key having legs projecting through said discs, and locking bolts slidably mounted in a passage through the

board and having their inner ends pivoted to said legs, and a spring in said opening co-acting with said bolts for normally holding them projected.

3. For use with a board member having a hole through it and having aligned passages projecting at right angles from said hole, locking bolts received in said passages and having offset ends in said hole and a key rotatably mounted on said board having legs projected through said hole and pivoted to said offset ends.

4. For use with a board member having a hole through it and having aligned passages projecting at right angles from said hole locking bolts received in said passages and having offset ends in said hole, a key rotatably mounted on said board having legs projected through said hole and pivoted to said offset ends and a spring element having its end secured to the board and having spiral portions integrally connected by a middle member extended around said legs.

5. A retractable bolt construction comprising a pair of disks adapted to lie against opposite sides of a board having a hole there-thru, said disks having portions extending into the hole and fitting the interior surface thereof so that the disks are positioned and rotatably mounted relative to the hole, a key having legs extending off center thru said disks, means on the key to retain the disks against the board, bolts having their inner ends pivoted to said legs, means for slidably supporting said bolts adjacent their outer ends, the board having passageways intermediate the legs of the key and said means for slidably supporting the bolts, said passageways being substantially larger in cross section than the cross sectional area of said bolts and means within said hole to retain said bolts in extended position, said last means comprising a double spiral spring having ends embedded in the board at the periphery of the hole therein and an intermediate portion extending around the legs of said key.

6. A retractable bolt construction comprising a pair of disks adapted to lie against opposite sides of a board having a hole there-thru, a key having legs extending off center thru said disks, bolts having their inner ends pivoted to said legs, means for slidably supporting said bolts adjacent their outer ends, and means within said hole to retain said bolts in extended position.

SERN MADSEN.
